(57) **CLAIM**

The ornamental design for an outdoor lighting fixture, as shown and described.

DESCRIPTION

FIG. 1 is a front, right and top perspective view of an outdoor lighting fixture, showing our new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a folded-down perspective view of FIG. 1;

FIG. 10 is another folded perspective view of FIG. 9;

FIG. 11 is another rotationally folded perspective view of FIG. 9;

FIG. 12 is another rotated perspective view of FIG. 12; and,

FIG. 13 is an enlarged view of portion 13 of FIG. 1 thereof. The broken lines shown in the drawings illustrate portions of the outdoor lighting fixture that form no part of the claimed design.

The dot-dash broken lines depict the boundaries of the enlargements that form no part of the claimed design.

1 Claim, 13 Drawing Sheets
